PORATION OF PENNSYLVANIA

VACUUM-TUBE CIRCUITS

Application filed April 15, 1925. Serial No. 23,429.

This invention relates to vacuum tube devices and particularly to vacuum tube generators of very high frequencies.

It is an object of this invention to distribute the heating effect of the space current over a greater extent of the filament, whereby the life of the tube is increased.

It has been found that with very short waves, the results obtained are better if provision is made for the space current to pass out of the tube over both ends of the filament, instead of over one end only.

It is usual in oscillation generators to provide an oscillating circuit, one point of which is at a potential but slightly different from that of the ground. Owing to difficulties in exact balancing, it is not possible to have the potential of said point exactly that of the ground. A metallic connection, from the point intended to be at ground potential, to the ground will, therefore, carry some high frequency current. It is a further object of this invention to provide for conveying this high frequency current, over two paths, from the ground to the two ends of the filament.

Other objects of the invention will be apparent from the following detailed description and the accompanying drawing in which

The single figure is a diagrammatic view of circuits and apparatus embodying this invention.

The vacuum tube 1 has a filament 2 supplied with heating current from a source 3. This source is illustrated as a direct-current generator, but it is evident that a battery or any other source of direct-current energy may be employed.

The tube 1 has a plate 4 which forms one terminal of the plate circuit supplied from the direct-current source 5. The circuit, including the direct-current source, comprises a choke coil 6, and is connected to the oscillating circuit 7 through a reactor 8. This reactor is illustrated as a condenser but an inductor may also be used.

The oscillating circuit 7 comprises a condenser 9, which may be the capacity of an antenna if desired, and an inductor 11 in parallel with the condenser 9.

A tap 12 is adjustably connected to the in-

ductor 11. Preferably this connection is at the electrical center of the inductor, whereby the potential of the tap 12 is only slightly different from that of the ground 13. It is difficult to make this adjustment with such nicety that this slight difference of potential is less than approximately 100 volts in a high potential sending station, but potentials at this midpoint which do not exceed a few hundred volts are not serious.

A tap 14 near the end of the inductor 11, opposite the end connected to the condenser 8, affords a connection for the grid 15 of the tube 1. This connection includes a grid-biasing device. Any form of grid-biasing device, such as a battery, may be used. I have chosen for illustration a condenser 16 in parallel with a high resistance 17.

The filament 2 has two conductors extending to the outside of the tube 1, one of said conductors for each end of the filament. A condenser 18 is connected to one of said conductors and to the ground. As illustrated, a connection to the ground is by way of the conductor 12, which is united to the conductor 75 extending to the other end of the filament. It is, however, obvious that the condenser 18 may be provided with a distinct ground if desired. The condenser 18 acts as a stopping condenser, preventing the short circuit of 80 the source 3 of heating current.

In the operation of the device, oscillations are set up in the circuit 7 and maintained by energy supplied from the source 5. The tube 1 generates these oscillations in a way that is familiar to those skilled in the art and need not be recited here. As a consequence of this action, a high-frequency component is present in the space current between the plate 4 and the filament 2. This high-frequency component may constitute the major part of the energy present in the space current.

The heating effect of the space current is added to the heating effect of the current from the source 3. If all of the space current 95 were obliged to pass out of the tube at one end of the filament, this end of the filament would fail more quickly because of the excessive deterioration at this point. The present invention causes the radio-frequency space 100

current to divide, passing out of the tube by both ends of the filament. Its heating effect is, therefore, distributed over a greater portion of the filament and the life of the filament 5 will be longer on this account.

The impedance offered by the condenser 18 to the high-frequency space current is small. For a high-power set working at a wavelength of about 90 meters, I have found .25 10 microfarad enough for this condenser, although it can, without disadvantage, be as large as two microfarads. The condenser can readily be so designed that the space current divides practically equally between the two 15 exits from the tube. Even when this is not done, the advantages of this invention can be secured by making the condenser of such size that a substantial portion of the space current passes throughout the condenser.

20 Many variations in the application of this invention and in the details of construction will readily occur to those skilled in the art. The specific illustration and description of only a single form is not intended as a limitation. 25 No limitation except that required by the prior art or explicitly stated in the claims is intended.

I claim as my invention:

1. In an oscillator, a vacuum tube having 30 three electrodes, namely, a plate, a filament and a grid, a source of heating current for said filament, an oscillation circuit, a source of energy, means so relating said oscillation circuit, said electrodes and said source that 35 oscillations are maintained in said oscillation circuit, said means including a conductor uniting one end of said filament to a point of small potential in said oscillating circuit, said conductor being grounded, and means 40 including a condenser for grounding the other end of said filament.

2. In a vacuum-tube radio-frequency generator, a cathode having two terminals external to the tube, a radio-frequency tuned 45 circuit, a connection from the anode to the source of power, a connection of smaller impedance to radio frequency than to low frequency extending between said terminals and a common connection distinct from said 50 terminal connection maintaining one of said terminals, a point of said tuned circuit and one pole of said source at ground potential.

3. In combination, a power-tube device 55 adapted to generate oscillations at radio-frequencies, said tube-device comprising a cathode having external terminals, a large condenser permanently connected between said terminals, and means distinct from said condenser for maintaining one of said terminals 60 at ground-potential.

In testimony whereof, we have hereunto subscribed our names this 6th day of April, 1925.

ROBERT L. DAVIS.
DONALD G. LITTLE.
